The ornamental design for a writing surface and enclosure for supplies, as shown and described.

DESCRIPTION

FIG. 1 is a right front perspective view of the writing surface and enclosure for supplies;

FIG. 2 is a top plan view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a bottom view thereof;

FIG. 8 is a right front perspective view thereof shown in the open position;

FIG. 9 is a right front perspective view of a second embodiment of the writing surface and enclosure for supplies;

FIG. 10 is a right front perspective view thereof shown with the frame in the open position;

FIG. 11 is a left side elevational view thereof;

FIG. 12 is a top plan view thereof;

FIG. 13 is a right side elevational view thereof;

FIG. 14 is a front elevational view thereof;

FIG. 15 is a rear elevational view thereof;

FIG. 16 is a bottom view thereof; and,

FIG. 17 is a right front perspective view thereof shown in the open position.

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 13

FIG. 14

FIG. 15

FIG. 16

FIG. 17

UNITED STATES PATENT AND TRADEMARK OFFICE
CERTIFICATE OF CORRECTION

PATENT NO. : Des. 360,894

DATED : August 1, 1995

INVENTOR(S) : Robert S. Volk, Joseph A. Marino

It is certified that error appears in the above-identified patent and that said Letters Patent is hereby corrected as shown below:

On the title page item [57], line 1, "desing" should be --design--.

Signed and Sealed this
Third Day of October, 1995

Attest:

BRUCE LEHMAN
